UNITED STATES PATENT OFFICE

WILLIAM C. HIERING, OF NEWARK, NEW JERSEY, ASSIGNOR TO J. E. MERGOTT COMPANY, OF NEWARK, NEW JERSEY, A CORPORATION OF DELAWARE

BAG FASTENER

Application filed December 8, 1931. Serial No. 579,715.

This invention relates to ladies' hand bags having frame members, and more particularly to means for fastening such frame members together.

5 The usual fastening devices for ladies' hand bags depend to a large extent upon the resiliency of the bag frame members for efficient operation. The bag frame members are hinged together, and obviously repeated

10 distortion of the frame members during the opening and closing of the bag has a damaging effect upon the hinge connection, and results in non-alinement of the frame members, and, ultimately in poor operation of 15 the fastening means, because of the impairment of the resiliency of the frame members.

Such fastening devices are also susceptible to easy manipulation by pickpockets, as it is generally only necessary to distort such 20 frame members to open the bag.

It is, therefore, an object of this invention to provide a bag fastening device, which does not rely upon the resiliency of the frame members for proper operation.

25 A further object is the provision of a bag fastening device which is simple in structure and which may be readily attached to standard bag frame members without material alteration.

30 These and other advantageous objects, which will later appear, are accomplished by the simple and practical construction and arrangement of parts hereinafter described and exhibited in the accompanying drawings, forming part hereof, and in which:

35 Figure 1 represents a perspective view of a hand bag embodying the preferred form of my invention,

40 Figure 2 represents a front view of the bag fastening device shown in Figure 1,

Figure 3 represents a rear view of the fastening device,

45 Figure 4 represents a rear view of the fastening device detached from the frame member,

Figure 5 represents a horizontal sectional view showing the position of the elements of the fastening device when the bag is open,

50 Figure 6 represents a horizontal sectional

view of the fastening device when the hand bag is closed,

Figure 7 represents a perspective view of a modified form of the invention,

Figure 8 represents a rear view of the 55 modified form of my invention,

Figure 9 represents a horizontal sectional view of the modified form of my invention, and

Figure 10 represents a side elevational 60 view of the modified form of my invention.

Referring to Figures 1 to 6, which show the preferred form of my invention, it will be seen that the bag fastening device is mounted on a pair of outwardly opening 65 hingedly connected channelled U-shaped frame members 11 and 12. Attached to the frame members 11 and 12 is a bag covering material 13, such as leather, fabric or the like, the bag covering material being secured 70 in the channels of the frame members and folded over the outer walls 15, and 16 of the frame members, to completely conceal said outer walls 15 and 16.

75 Fixed to the inner surface of inner wall 17 of frame member 11 is a small plate 18 which is bent outwardly to provide a guide slot to receive the vertical leg 19 of a bracket 20. The leg 19 is provided with prongs 21 which pass through apertures in the bottom of the 80 channel of the frame member 11, the prongs being bent over or upset as shown in Figure 3, to securely hold the bracket on the frame member.

85 The bracket 20 has an integral off-set arm 22 which is fixed to a casing 23, which may be of semi-spherical shape as shown in the drawings, or of any other desired shape. As shown in Figure 1, the open side of the casing fits snugly against the side of the hand 90 bag.

95 The casing 23 is provided with slot 24, in which a lever 25 moves, the latter being pivoted to the lower edge of casing 23, (see Figs. 2 and 3). The lever 25 is engaged by a bowed leaf spring 26 which constantly urges the lever to the upper extremity of slot 24, the spring 26 being attached to the inner wall of the casing.

Attached to the inner wall 14 of frame 100

member 12 is a plate 27 having a horizontal tongue 28 with a recess 29 and a cam nose 30.

In operation, when the frame members are brought together to close the hand bag, the nose 30 cams over the lever 25 against the action of spring 26 to cause the lever 25 to snap into the recess 29 where it is held by the spring 26. The frame members are now securely fastened together and may be released only by manually moving lever 25 out of recess 29.

From the above description it will be seen that I have provided a simple and effective bag fastening device which may be readily attached to standard bag frame members without material alteration of the frame members. The manner of attaching bracket 20 to wall 17 by inserting the leg 19 in the guide slot formed by the wall 17 and plate 18 obviously enables the ready changing of a casing of one design for a casing of a different design whenever so desired. Also, the fastening devices may be made in many shapes and entirely independent of the frame members, so that, when assembling a bag, a fastening device of the desired shape may be selected and readily attached to the standard frame member.

In Figures 7 to 10 a modified form of the invention is shown wherein a pair of inwardly opening channelled U-shaped frame members 40, 41 are hingedly connected. Bag covering material 42, such as leather, fabric or the like is secured in the channels by any desired or well known means such as by clamping or sewing.

Attached to the outer side wall 43 of frame member 40 is a casing 44, preferably semi-spherical in shape, although the casing may be of any suitable shape without departing from the spirit of the invention. The casing is provided with a horizontal semi-circular slot 45, and has attached to its inner wall a bowed leaf spring 46, carrying a lug 47, the spring constantly urging the lug to a position to engage a bar 48 when the latter is moved in the slot.

The extremities of the bar 48 are attached to the chains 50, 51, the chain 50 being connected to a lug 49 fixed to the frame member 40, and chain 51 carrying a knob 52 to facilitate the manipulation of the device.

Attached to frame member 41 is a plate 53 having a horizontal tongue 54 with a cam nose 55 and slot 56.

In operation, to close the hand bag, the frame members are brought together to cause tongue 54 to enter the casing 44. The bar 48 is then moved in the slot 45 to the position shown in Figs. 8 and 9, where it is maintained by the spring urged lug 47. The bar also enters slot 56 of tongue 54 and prevents the latter from being withdrawn from the casing, and the bag may now be opened only

by manually moving the bar 48 to force the lug 47 backward to enable the bar 48 to be moved in slot 45 to a position free of the casing 44.

It is a popular practice to make hand bags with outwardly opening channelled U-shaped frame members as indicated in Figure 1. In such bags the covering material is clamped or sewed in the channels, the material completely covering the outer walls of the frame members, so that when the bag is closed the frame members are entirely concealed. Heretofore, such frame members have been provided with fastening devices attached to the inner side walls, such as walls 14, 17 of the frame members, and have relied for their effective operation upon the resiliency of the frame members. From the description of my invention set forth above, it is apparent that I do not rely upon the resiliency of the frame members; and also my invention enables a bag to be first completely covered and finished with a suitable material before attaching my bag fastening device.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In combination with a pair of hingedly connected bag frame members, a fastening device comprising a bracket, means on one of the frame members to guide the bracket, means for fixing the bracket to the frame member, a casing, having a slot, connected to the bracket and abutting the frame member, a tongue attached to the other frame member and arranged to enter the casing when the frame members are brought together, a lever pivotally mounted on the casing, said lever moving in the slot and engaging the tongue to prevent withdrawal of the latter, and spring means urging the lever into engagement with the tongue.

2. In combination with a pair of hingedly connected bag frame members, a fastening device comprising a casing attached to one of the frame members, said casing having a slot, a tongue attached to the other frame member and arranged to enter the casing, a lever pivoted on the casing and movable in the slot, said lever preventing withdrawal of the tongue from the casing, and spring means in the casing urging the lever into engagement with the tongue.

3. In combination with a pair of hingedly connected bag frame members, a fastening device comprising a casing, means to detachably mount the casing on one of the frame

members, a tongue attached to the other frame member and arranged to enter the casing, a lever pivoted to the casing and engaging the tongue to prevent its withdrawal from the casing, and means in the casing normally urging the lever into engagement with the tongue.

4. In combination with a pair of hingedly connected bag frame members, a fastening device comprising a casing attached to one of the frame members, said casing having a slot, a lever pivoted to the casing and movable in the slot, a tongue attached to the other frame member and arranged to enter the casing, said lever engaging the tongue to prevent withdrawal of the latter when the lever is in one extreme position of the slot, and a bowed leaf spring constantly contacting and urging the lever to said extreme position in the slot.

5. In combination with a pair of outwardly opening channelled U-shaped bag frame members, means attached to the inner wall of one of the members to provide a guide, a bracket having a leg positioned in the guide, prongs on the leg to rigidly attach the bracket to the member, a casing having a slot fixed to the bracket and abutting the outer side wall of the member, a lever pivoted to the casing and movable in the slot, a slotted tongue attached to the other frame member and arranged to enter the casing, and spring means in the casing to urge the lever into the slot in the tongue to prevent withdrawal of the tongue from the casing.

6. In combination with a pair of hingedly connected frame members having outwardly opening channels, a bracket, means on one of the frame members to detachably secure the bracket to the frame member, a casing attached to the bracket, said casing having a slot, a tongue attached to the other frame member, means movable in the slot to prevent withdrawal of the tongue from the casing when the frame members are brought together, and means in the casing to urge said movable means into engagement with the tongue.

This specification signed this seventh day
50 of December, 1931.

WILLIAM C. HIERING.
